COVER WRENCH

Mathilde Giesinger, New York, N. Y.

Application September 26, 1934, Serial No. 745,500

1 Claim. (Cl. 81—3.1)

This invention relates to improvements in cover wrenches, being particularly directed to a device applicable for loosening and tightening screw type or friction covers for jars.

5 Broadly, it is an object of this invention to provide a cover wrench incorporating a plurality of jaws, one fixed and one movable, adapted to peripherally engage a cover of the screw or friction type to loosen or tighten the same with respect to the jar on which it is disposed, the movable jaw being reciprocable with respect to the fixed jaw through the longitudinal movement of the wrench handle upon rotation of the latter.

Specifically, it is an object of this invention to 15 provide for a cover wrench incorporating fixed and movable jaws, the said movable jaw being reciprocable along a guide through the actuation of the rotatable handle, such handle or a part thereof being interiorly threaded to cooperate 20 with threads on a jaw support, whereby upon rotation the handle simultaneously is longitudinally displaced.

These and other advantages, capabilities and features of the invention will appear from the 25 subjoined detailed description of one specific embodiment thereof, illustrated in the accompanying drawing, in which

Figure 1 is a side elevation partly in section showing the wrench.

30 Figure 2 is a plan view partly in section of the device.

Figure 3 is an end view in section taken along lines 3—3 of Figure 1.

Figure 4 is a side elevation partly in section of 35 a modified form of device.

Referring to the reference characters in the drawing, numeral 10 represents the wrench shank rectangular in cross-section, as shown in Figure 3, and having mounted at one end thereof a fixed 40 gripping jaw 11, said jaw comprising a body portion 12, through which pass fastening means 13, for attaching the gripping jaw to the shank 10 and having a plurality of wings 14 and 14' extending therefrom, such wings having serrated 45 gripping portions 15. As shown in Figures 1 and 2 the gripping jaw 11 is so formed as to provide for an offset of the wings 14 and 14' with respect to the body 12, thereby to provide for disposal at a considerable depth of the gripping members 50 with respect to the top of the cover to be acted on.

The shank is threaded from a point distant to the end thereof carrying the fixed gripper jaw to its other end, as at 16, and on the shank there is disposed movable jaw 17 having a body portion 18 55 and offset wing portions 19 and 19' similar in

formation and relation with respect to the body 18 as are the wings 14 and 14' with respect to the body 12, the wings of the movable gripper jaw being oppositely directed to those on the fixed jaw. Integral with body 18 of the movable gripper jaw 17 is formed guide 20, the construction of which is that of a substantial right angle as indicated in Figure 3, the respective interior peripheral surface of which is disposed adjacent the peripheral surface of the threaded portion 16 of 10 the shank 10, there being provided a slidable fit between the guide and the shank. Cooperating with the threaded free end of the shank 10 there is provided a handle 21, the interior of which is grooved to provide a thread 22 circular in formation, such thread being of the same pitch as the thread on the shank, whereby rotation of the handle with respect to the shank will cause a reciprocation of the handle with respect to the shank, the open end of the handle as at 23 having formed therein a bearing surface adapted to 15 contact with the end 24 of the guide member 20, thereby to cause a longitudinal reciprocation of the guide member carrying the movable gripping jaw with respect to the shank upon rotation of 20 the handle.

It should be noted in the form shown in Figures 1 to 3, that the movable jaw incorporating the guide 20 is freely slidable on the shank 10 and can be displaced along the shank at the 30 threaded or non-threaded portions thereof by mere physical manipulation, independent of the actuation of the handle. This feature is provided so that when covers of various sizes are involved, as is commonly found in household operations, the movable gripping jaw may be rapidly displaced along the shank so as to form a temporary grip, after which the handle is rotated about the shank to cause upon the handle's longitudinal movement the contact of the bearing 40 at the open end thereof with the end of the guide on the gripper member, thereby to transmit displacement and pressure upon further actuation of the handle to firmly lock the movable gripper jaw in conjunction with the fixed gripper 45 jaw to a cover. It should be noted in this modification, that the handle may displace the movable gripper jaw towards the fixed gripper jaw upon actuation thereof, but that the movable gripper jaw is not returned or directed away 50 from the fixed gripper jaw by rotation of the handle in a direction opposite to its locking movement.

To provide for a displacement of the movable gripper jaw in both directions with respect to 55

the fixed gripper jaw, there is shown in Figure 4 a modification incorporating a lug or projection 25 depending from the movable jaw carrying a pin 26 angularly disposed with respect thereto, 5 which pin is adapted to ride in groove 27 formed on the inner periphery of handle 23 adjacent the open end thereof. Through the provision of this locking mechanism the movable gripping jaw is directly interlocked with the handle, thereby 10 to provide for reciprocation of the movable gripping jaw with respect to the fixed gripping jaw upon relative displacement in opposite directions of the handle, upon rotation of the same with respect to the shank.

15 It is obvious that various changes and modifications may be made to the details of construction without departing from the general spirit of the invention as set forth in the appended 20 claim.

I claim:

In a device of the class described, a shank, a

gripping member fixed at one end thereof, a movable gripping member slidable along said shank, threads formed on the free end of said shank, a hollow handle interiorly threaded to cooperate with the threads of said shank, whereby rotation 5 of said handle with respect to said shank causes longitudinal reciprocation of said handle, a movable gripping member slidable along said shank and disposed between the fixed gripping member and said handle, guide means integral with said 10 movable gripping member, and forming a sleeve with respect to said shank, means for interlocking said movable gripping member with said handle, whereby reciprocation of said handle upon rotation thereof with respect to the shank 15 produces reciprocation of the movable gripping member with respect to the fixed gripping member, said means comprising a projection extending from said movable gripping member disposed in a peripheral groove formed interiorly of said 20 handle.

MATHILDE GIESINGER.
